UNITED STATES PATENT OFFICE.

JOHN C. CHAPMAN, OF BOSTON, MASSACHUSETTS.

METAL-BENDING MACHINE.

SPECIFICATION forming part of Letters Patent No. 350,115, dated October 5, 1886.

Application filed March 20, 1886. Serial No. 196,092. (No model.)

To all whom it may concern:

Be it known that I, JOHN C. CHAPMAN, a citizen of the United States, residing at Boston, in the county of Suffolk and State of Massachusetts, have invented certain new and useful Improvements in Metal-Bending Machines, of which the following is a specification.

My invention has for its object to improve the supporting trusses of that class of metal-bending machines in which long rollers are used; also to provide a means for sustaining the upper roll of the set when one end of the same is not supported by its journal-box; also to so construct the machine that the housing 15 that supports one of the journal-boxes of the upper roll may be swung outwardly, and thus leave the upper roll and its journal-box suspended above and free from the lower rolls; also in hanging the journal-boxes of two of the 20 rolls on swinging links, so that although the rolls may be adjusted in relation to each other, still their gears will engage with each other accurately on their pitch-lines; also to adapt to the journal-boxes oscillating socketed steps 25 for the adjusting set-screws; also to provide the upper roll with the supplemental journal-pin and a device for holding said pin. I attain these objects by the mechanism shown in the accompanying drawings, in which—

Figure 1 is a view of my machine, partly in elevation and partly in section. The end shown in section for convenience I call the "arm end," while the end shown in elevation I call the "driving end." Fig. 2 is an elevation of the 30 driving end of the machine. Fig. 3 is an elevation of the arm end of the machine. Fig. 4 is an elevation of the arm end of the machine, the "arm" being represented as swung off so as to leave one end of the upper roll free. Fig. 5 is a view showing my machine in horizontal section, taken on line $z z$ of Fig. 1. Fig. 6 is a cross vertical section taken on line $x x$ of Fig. 1. Fig. 7 is a cross vertical section taken on line $y y$ of Fig. 1. Fig. 8 shows a 40 plan view of the gear end of the machine. Fig. 9 is a detail vertical section. Fig. 10 is a horizontal section taken on a line, $v v$, of Fig. 6.

My present invention is an improvement on a machine for which Letters Patent of the 45 United States were granted to me March 9, 1875, No. 160,647, subject, "Improvement in Metal-Bending Machines."

In all the drawings, A A represents the end parts of the frame of the machine, these parts being held together by the tie-rods B B. In 55 this machine three rolls are used, namely, two lower ones, b and c , and an upper one, a . The ends of the upper roll, a , and of the lower roll b are hung on swinging links f and f' , Figs. 4 and 7, the links f and f' that hold the ends of the 60 upper roll being pivoted in fixed bearings, Figs. 6 and 7, said bearings being concentric with the reversing-gear n , Fig. 2, so that although the upper roll, a , may be raised or lowered, its gear a^2 , Fig. 2, will still properly 65 engage with the reversing-gear n . The gear n being on a fixed bearing engages properly with the gear m , which in its turn is driven by the gear c^2 on the lower roll c .

o , Fig. 2, is the driving-gear, and operates 70 all the others. The lower roll b is hung on links f and f' , Figs. 7 and 8, one at each end, said links swinging on fixed bearings, Figs. 2 and 7, which are concentric with the driving-gear o , Fig. 2, so that although the roll b may be adjusted 75 its gear b^2 will always mesh properly with the driving-gear o .

The two adjustable rolls are hung in sliding boxes, all of which are substantially like those shown at a , Figs. 1, 2, 6, 7, and 10, the 80 cross-section of each being similar to the cross-section shown in Fig. 10—that is, each box is arranged to slide on the frame A. The ways, as indicated at a^2 , Fig. 10, fit loosely so that the boxes have considerable play and may adjust 85 themselves to accommodate the bodily movement of their respective rolls on the swinging link. As these boxes are moved by the screws d and d' , which are rigid in the frame A, I arrange for their motion while adjusting 90 the rolls by putting an oscillating step, e , Figs. 7 and 9, for the lower enlarged end of the screw to operate in, there being a space at the upper part of the box for the neck of the screw to swing in, so that in lowering or lifting 95 the boxes in the act of adjusting the rolls the said boxes can swing as much as may be desired in accommodating themselves to the movement of the rolls.

To prevent the rolls from springing I truss 100 each one with rods, as indicated at a^3 , Fig. 1. These truss-rods are connected at each end to the journal-boxes for the adjustable rolls a and b , but the truss-rod belonging to the fixed

roll *c*, Figs. 2 and 3, is fastened directly to the frame of the machine, as shown. As the two adjustable rolls *a* and *b* are prevented from springing by the same means, I will describe one, *a*, only. The rod *a'* is connected at its ends to the boxes *a'*, and as the boxes move with the roll and to the desired extent independently of the frame of the machine and embrace the saddle-pieces *a⁴ a⁵ a⁶*, as well as the boxes *a' a'*, which they are buttressed against, it will be readily understood that the adjustable rolls with their re-enforcing parts—viz., rods and saddles—are to a certain extent independent of the frame, and in this respect differ from the similar parts described in my former patent, already referred to.

The rod *h*, Figs. 1, 6, and 9, serves to assist in holding the roll *a* suspended when the arm or frame *A'* is swung off, and is fastened at one end to the projection *h'* on the box *a'*, Fig. 9, and at its other end to the projection *a⁸* of the saddle *a⁶*. The parts *a'*, *a⁵*, and *a⁶* of the saddles are not connected, but form with each other what may be termed "buttress-joints," and as the extreme ends of *a⁴* and *a⁶* rest against the boxes *a'*, and as the said boxes *a' a'* are held firmly by the rod *a'* the whole combination—viz., box *a'*, saddles *a⁴ a⁵ a⁶*, and box *a'*—is clamped together longitudinally with a lateral pressure on the middle saddle, *a⁵*.

To facilitate taking out the plates when bent, from between the rolls, I have the following device, particularly shown in Figs. 3, 4, and 5, in which *A'* represents a supplemental frame, which is pivoted to the main frame *A* by the bolt *A²*, and is held at its other end by the bolt *A³*, which engages with a slot, as shown in Fig. 5. This swinging frame *A'* has upon it the screw *d*, which, when in place, adapts and holds the journal-box *a'* in position. The journal-box *a'*, referred to, does not swing out with the frame *A'*, but is left and held in position by the rod *a'*, as has been stated.

To assist in holding the free end of the roll *a* in place I use a pin, *g'*, Figs. 1 and 5. This pin *g'* enters a hole made in the end of the roll *a*, as shown, and, as in a working-machine it is quite heavy, I support it by a compound lever, *K K'*, Figs. 3 and 4. This lever consists of a main part, *K*, holding the pin *g'*, 45 hung on a pivot, *K'*, Fig. 3, and a manipulating-lever, *K'*, said lever *K'* being hung on pivot *K'*, and acting cam-like in a slot made in the outer end of the lever *K*, as shown in Fig. 3. By moving the lever *K'* the lever *K* 50 that holds the pin *g'* can be moved, so that the pin *g'* may be raised or lowered as may be desired, in order to place it in the end of the roll *a* for the purpose of assisting in holding the roll *a* in place while the machine is bending a plate.

I claim—

1. In a metal-bending machine, the combination of the roll *a*, rod *a'*, and saddles *a⁴ a⁵ a⁶* with the boxes *a' a'*, all arranged to operate 65 together, substantially as described, and for the purpose set forth.

2. In a metal-bending machine, the combination of the roll *a*, rod *a'*, saddles *a⁴ a⁵ a⁶*, and rod *h* with the boxes *a' a'*, all arranged substantially as described, and for the purpose 70 set forth.

3. In a metal-bending machine, the combination of the rolls *a b c* and the swinging frame *A'* with the compound lever *K K'* and pin *g'*, 75 substantially as described, and for the purpose set forth.

In testimony whereof I have signed my name to this specification, in the presence of two subscribing witnesses, on this 17th day of March, 80 A. D. 1886.

JOHN C. CHAPMAN.
